UNITED STATES PATENT OFFICE.

JAMES B. HILL, OF RACELAND, LOUISIANA.

TRACTOR.

1,105,562.

Specification of Letters Patent. Patented July 28, 1914.

Application filed July 25, 1912. Serial No. 711,509.

To all whom it may concern:

Be it known that I, JAMES B. HILL, a citizen of the United States, residing at Raceland, in the parish of La Fourche and State of Louisiana, have invented a new and useful Tractor, of which the following is a specification.

This invention relates to tractors particularly designed for use in tilling soft soil such as reclaimed marsh lands. Machines for this purpose must be comparatively light and must present broad bearing surfaces to the ground or they will otherwise sink into the soil to undesirable depths and thus be rendered practically useless.

One of the objects of the present invention is to provide a machine of this character utilizing a broad apron in lieu of the ordinary drive wheels, said apron being so proportioned as to bear downwardly upon an extensive surface.

Another object is to so connect the apron to the main structure of the machine as to permit it to oscillate readily about a transverse axis and thus pass freely over an uneven surface.

Another object is to provide a drive apron the lower flight of which is curved longitudinally so as to facilitate the turning of the machine.

Another object is to provide improved mechanism whereby motion is transmitted from the motor to the propelling apron.

Another object is to provide novel means for connecting a gang of plows to the tractor, mechanism being provided whereby said gang can be readily shifted into or out of engagement with the soil.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a side elevation of the tractor and showing a gang of plows connected thereto. Fig. 2 is a plan view of the mechanism shown in Fig. 1. Fig. 3 is an enlarged elevation of that side

of the tractor opposite to that shown in Fig. 1. Fig. 4 is an enlarged plan view of the tractor. Fig. 5 is an enlarged view of a portion of the apron propelling mechanism. Fig. 6 is an enlarged transverse section through a portion of the apron and its runners. Fig. 7 is a side elevation of a portion of the apron. Fig. 8 is a side elevation, on a reduced scale, of one of the runners, the axle bearing being removed. Fig. 9 is an enlarged side elevation of the axle bearing. Fig. 10 is an end elevation of the axle. Fig. 11 is a perspective view of one of the saddles used in connection with the axle. Fig. 12 is a section through a portion of one of the runners and showing the position of the shaft and sprocket relative thereto.

Referring to the figures by characters of reference 1 designates the main frame of the machine, the same being formed of channel or I beams suitably connected. An opening 2 is formed in the front portion of the platform 3 which is carried by the frame 1 and erected on this platform and extending over the opening are upwardly converging supports 4 preferably arranged in front and rear pairs and provided with suitable braces, as at 5. These supports are connected to a cap 6 into which projects a pivot bolt 7 extending upwardly from a cross head 8 which is mounted, at its ends, upon upwardly converging standards 9 which are secured to the sides of a frame 10 located below the opening 2. Bearings 11 are carried by the sides of the frame 10 and receive the axle 12 of the front or steering roller 13. A ring 14 is secured to and extends around the frame 10 and this ring is engaged by anti-friction wheels 15 journaled at suitable points in brackets 16 secured to the walls of the opening 2 and thus serve to prevent the frame 1 from tilting relative to the frame 10.

A transverse shaft 17 is journaled under the frame 1 and back of the roller 13, this shaft being provided with a drum 18 to which are secured the ends of a chain 19. Said chain is guided partly around guide sheaves 20 supported under the frame 1 and the chain is extended around the ring 14 and is supported at regular intervals, by outstanding substantially U-shaped brackets 21 secured to the outer face of the ring. This chain may be secured, at an intermediate point, to the ring 14 so that, when the drum 18 is rotated in one direction, one end portion of the chain 19 will be wound thereon.

while the other end portion will be unwound, this resulting in rotating the ring 14 and the roller 13 within the opening 2. For the purpose of facilitating the actuation of shaft 5 17 and drum 18, a worm wheel 22 is secured to the shaft 17 and is engaged by a worm 23 located at the lower end of a steering shaft 24. This shaft projects upwardly above the platform 3 and is provided, at its upper end, 10 with a hand wheel 25 or the like whereby the shaft can be turned readily.

Secured to and extending transversely of the frame 1 are parallel channel beams 26 having their flanges extended toward each 15 other. Connecting the bottom flanges of these beams is a saddle plate 27 having depending end flanges 28. Similar plates 29 are secured to the outer faces of the beams 26 and have terminal flanges 30 outstanding 20 therefrom. These plates 27 and 29 are adapted to bear upon the walls of circular openings 31 formed between castings 32 or the like which are secured to parallel up-standing strips 33 and to a cross strip 34. 25 The upstanding strips 32 are secured, at their lower ends, to the lower curved beams 35 while the upper ends of said strips are secured to straight upper beams 36. These upper and lower beams are connected at one 30 end, by an arcuate beam 37 and the other ends of the beams 35 and 36 are connected by an end strip 38. These beams 35, 36 and 37 and the end strip 38 form runners and the upstanding strips 32 and their connections 34 are preferably located adjacent the centers of the runners. Crossed braces 39 may be interposed between the beams 35 and 36 for the purpose of reinforcing the runners and the two runners, which are located adjacent the respective sides of the frame 1, may be connected by cross beams 40 whereby said runners will move as one body about the longitudinal axis of the axle made up of beams 26. The flanges 28 and 45 30 lap the upstanding strips 32 and the cross strip 34 and thus prevent lateral displacement of the runners relative to the frame 1.

The lower or active faces of the runners 50 are provided, along their centers, with outstanding flanges 41, these flanges entering between rollers 42 which are mounted on pins 43 which serve to pivotally connect the links 44 of oppositely disposed similar 55 chains, longitudinal displacement of the pins relative to the links being prevented by ears 45 which are struck from certain of the links and lap the ends of the pins. The corresponding links of the two chains are 60 disposed directly opposite each other and mounted on the pins 43 are brackets 46 secured to tread strips 47 which are adapted to be brought successively into contact with the ground when the endless chains are 65 actuated. In other words, these tread strips

46 and the endless chains constitute an apron designed to propel the machine forward, the anti-friction rollers 42 which move with the apron, being adapted to travel along the outer or active faces of the beams 70 35, 36 and 37.

A shaft 47 is journaled in bearings upon the end strip 38 and secured to this shaft, between its ends and in the same vertical planes with the flanges 41, are actuating 75 wheels or sprockets 48 designed to engage the rollers 42, there being longitudinal webs 49 between the teeth of the sprockets for projecting into the spaces between the rollers. Additional sprockets 52 are secured to the end portions of the shaft 47 and receive motion, through chains 53, from small sprockets 54 which are secured to a shaft 55. This shaft extends transversely of and is journaled on the frame 1 and is provided, at one end, with a large sprocket 56 adapted to receive motion, through a chain 57, from a small sprocket 58 secured to a counter shaft 59 journaled on and extending transversely of the frame 1. A large gear 60 is 90 secured to the shaft 59 and a large sprocket 61 is also secured to said shaft.

A motor 62 is mounted on suitable supports 63 carried by the frame 1 and the shaft 64 of the motor has a sprocket 65 which transmits motion, through a chain 66, to a sprocket 67 keyed or otherwise secured to a transverse shaft 68 on the frame 1. A clutch member 69 is loose on the shaft 68 and has a sprocket 70 secured thereto and engaged by a chain 71 extending from the sprocket 61. Another clutch member 72 is feathered on the shaft 68 and has a gear 73 secured thereto and which is normally out of mesh with the gear 60. By shifting the gear 73 away from gear 60, the clutch 72 can be brought into engagement with the clutch member 69 so as thus to couple the sprocket 70 to shaft 68. Thus motion will be transmitted from motor 62 to the sprocket 61 110 and the shaft 47 will be caused to rotate in one direction so as to drive the machine forward, as will be described hereinafter. By shifting the gear 73 in the opposite direction, the clutch member 72 will be moved 115 out of engagement with clutch member 69, thereby uncoupling the sprocket 70 from shaft 68. Further movement of the clutch member 72 will bring the gear 73 into mesh with gear 60 and, therefore, motion will be 120 transmitted from the motor 62 to gear 60 and the shaft 47 will be rotated in the opposite direction so as to drive the machine rearwardly. The wheel 74 of a band brake may be secured to the shaft 68, as shown, 125 thus permitting the operation of the machine to be controlled readily.

Under normal conditions, and with the clutch member 72 in the position shown in Fig. 4, the shaft 68 can rotate freely with- 130

out causing movement of the machine. When, however, the clutch member 72 is shifted into engagement with the clutch member 69, the shaft 47 will be rotated so as to cause the sprockets 48 to push the runners forward so that they will travel along the anti-friction rollers 42 carried by the lower flight of the endless apron. As the result of this action, the tread strips or blocks 46 will be brought successively into position under the lower beams 35 of the runners and will come ultimately into contact with the ground. As these strips or blocks extend practically throughout the width of the machine it will be seen that an extensive bearing surface is presented to the ground by them and it becomes possible, therefore, for the machine to travel over soft soil such as reclaimed marsh lands without sinking thereinto to an objectionable extent. By changing the sprockets 56 and 58, the speed of the machine can be varied at will.

It will be noted that the lower flight of the endless apron travels along curved beams 35. As a result the apron does not present a perfectly flat surface to the soil but presents a curved surface. This is important because it enables the machine to be more readily turned than where a plain surface is formed by the lower flight of the apron. As the runners can rock freely above the longitudinal axis of the transverse axle formed of the channel beams 26, it will be seen that the apron can pass freely over obstructions in the path thereof.

The tractor herein described is designed for various purposes among which may be mentioned the leveling of the tops of levees, and in the cultivation of reclaimed marsh land, the machine being used in the manner last stated, by drawing gangs of plows, or other soil engaging devices.

In Figs. 1 and 2 a gang of plows has been shown combined with the tractor. By referring to these figures it will be noted that side strips 75 are pivotally connected, as at 76, to hangers 77 depending from the sides of frame 1, these strips being connected, at their rear ends, by diagonally disposed beams 78 suitably connected by means of top plates 79. Beam sections 80 are bolted or otherwise secured to the bottoms of the beams 78 and hingedly connected to the rear projecting ends of these beam sections 80 are the beams 81 of plows 82. Levers 83 are pivotally connected to the beam sections 80 and are connected, by links 84, to the rear portions of the beams 81. Pivoted rack bars 85 are provided for the respective levers 83 and these bars are adapted to be engaged by spring pressed pawls 86 carried by the levers. Thus it will be seen that the plow beams can be secured in any desired positions after being adjusted

angularly about their connections with the sections 80. Snap pins 87 are preferably provided for connecting the links 84 to the beams 81 so that, should one of the plows strike an unyielding obstruction, the snapping pin 87 will break and thus permit the beam 81 to swing upwardly relative to the beam section 80 to which it is attached and without requiring corresponding movement of the lever 83. Snapping pins may also be used at any suitable points in the driving mechanism of the machine so that inadvertent stopping of the machine for any purpose will not result in damage to any of the parts thereof.

For the purpose of lifting the gang of plows out of engagement with the soil, a shaft 88 is extended transversely of the rear end of frame 1 and has chains 89 secured thereto and extending downward to the side strips 75. These chains 89 are adapted to be wound on the shaft 88, there being a worm wheel 90 on one end of the shaft and which is engaged by a worm 91 secured to one end portion of an actuating shaft 92. This shaft extends forwardly to a point where it can be conveniently reached by the operator and is provided with a hand wheel 93 or the like whereby it can be easily turned. Thus it will be seen, that by rotating shaft 88 in one direction, the chain 89 will be wound thereon and the frame of the gang of plows swung upwardly about the pivots 76. By paying out the chain the plows of the gang of plows can be lowered to extend any desired depth into the soil.

What is claimed is:—

1. In a tractor the combination with a frame, and a transverse axle, of connected runners mounted to oscillate upon the axle, a shaft journaled upon and extending transversely of the runners, an endless apron extending around the runners and including hingedly connected tread strips, spaced rollers movable with the apron, and sprockets upon the transverse shaft and engaging the rollers, there being webs upon the sprockets and adapted to be seated within the spaces between the rollers.

2. In a tractor, the combination with a main frame, of an axle including transversely extending oppositely disposed channel beams, flanged bearing strips secured to the beams, the flanges at the ends of said strips outstanding, connected runners having openings therein for the reception of the axle, said end flanges constituting means for preventing lateral displacement of the runners relative to the axle, an endless apron mounted upon the runners, and means for actuating the apron.

3. In a tractor, a runner having a depending longitudinal flange along the center of the bottom thereof, an endless apron extending around the runner and including

hingedly connected tread strips, a pair of spaced rollers extending between every two adjoining tread strips and movable with the apron, said rollers being movable along the 5 runner and said flange being extended between the rollers, and sprockets supported in line with the runner for engaging the rollers to actuate the apron.

4. In a tractor, the combination with a 10 frame and a transverse axle, of connected runners mounted for oscillation upon the respective end portions of the axle, there being a central longitudinal flange depending from each runner, parallel tread strips 15 extending under the two runners and

hingedly connected to form an endless apron, pairs of spaced rollers interposed between every two tread strips, one pair of rollers being disposed below each runner, the flange being extended between the rollers of each pair, and sprockets alined with the runners and engaging the rollers to actuate the apron. 20

In testimony that I claim the foregoing as my own, I have hereto affixed my signature in the presence of two witnesses. 25
